UNITED STATES PATENT OFFICE.

PURMORT BRADFORD, OF NEW HAVEN, CONNECTICUT, ASSIGNOR TO
SARGENT & CO., OF SAME PLACE.

FLUSH-BOLT.

SPECIFICATION forming part of Letters Patent No. 224,638, dated February 17, 1880.

Application filed December 26, 1879.

To all whom it may concern:

Be it known that I, PURMORT BRADFORD, of New Haven, in the county of New Haven and State of Connecticut, have invented a new 5 Improvement in Flush-Bolts; and I do hereby declare the following, when taken in connection with the accompanying drawings and the letters of reference marked thereon, to be a full clear, and exact description of the same, 10 and which said drawings constitute part of this specification, and represent, in—

Figure 1, front view; Fig. 2, side view; Fig. 3, rear view.

This invention relates to an improvement in 15 that class of bolts commonly termed "flush-bolts," such as are commonly used at the top and bottom of one of a pair of doors. These are usually constructed with some frictional device to hold them in their drawn position, 20 or in some cases with a latching device, which will hold the bolt in one direction, and a spring to hold it in the other; but in none is there that positive security for the bolt in both the drawn and thrown positions which is desirable 25 in this class of bolts. To produce this result is the object of this invention; and it consists in the construction, as hereinafter described, and particularly recited in the claim.

A is the plate or body of the bolt; B, the 30 bolt-head, which extends through the right-angular end c of the plate A, and from which the bolt-spindle D extends along the inside of the plate, supported and guided in a bearing, E, so as to be freely moved longitudinally from its drawn to its thrown position, and return. F is a knob or handle arranged upon the outside of and in suitable bearings in the plate, so as to be turned freely. On the inside of 35 the plate a cam, a, is arranged, attached to the knob, and so as to be turned with it. This 40 cam is provided with a crank-pin, b, from which

a connecting-rod, d, extends to the bolt-spindle D, as seen in Figs. 2 and 3. The two sides of the cam a are made straight, and onto each of these two sides one arm, e, of a doubled spring rests, as seen in Fig. 3, grooves being formed in the sides of the cam to prevent the spring slipping off. The two arms e extend from a coil, f, which is held fast to the plate. 45

When the bolt is thrown the crank-pin is at 50 its lowest point below the axis of the knob or cam a, and as seen in Fig. 3. Now if the knob be turned it will turn the cam, the springs e e will spread, and the bolt will be moved until the crank-pin b be at a point in the same 55 line, but above the axis of the cam, as seen in broken lines. In coming to this latter position the springs close upon the sides of the cam, but upon opposite sides to their first position. This enables the spring to hold the 60 cam in, and also tends to throw it to either of its extreme positions, so as to secure the bolt in either of its two positions, which positions are in vertical or longitudinal line of the bolt through the axis of the cam. 65

While a two-armed spring is the best, because each arm forms a support or resistance for the other, a spring with a single arm may be applied in the same manner.

I claim—

The combination of the plate A, the bolt and its spindle arranged thereon, with an external knob connected to and so as to revolve the cam upon the inside, the said cam connected to the bolt by a crank-connection, and 75 a spring bearing upon said cam, so as to hold the said cam and bolt in either of the extreme positions, substantially as described.

PURMORT BRADFORD.
